UNITED STATES PATENT OFFICE

2,568,576

COUNTERBALANCED CRANKSHAFT FOR
INTERNAL-COMBUSTION ENGINES

Julius E. Witzky, Stuttgart-Cannstatt, and Wolfgang S. Lang and Richard J. Jakob, Wendlingen-Neckar, Germany, assignors to the United States of America as represented by the Secretary of War

Application June 30, 1947, Serial No. 758,034

4 Claims. (Cl. 74—603)

1

This invention relates to crankshafts for internal combustion engines, and more particularly to counterweighted crankshafts to obtain the proper operating balance.

One of the objects of the invention is to provide an improved counterweight construction of internal combustion engines. Another object of the invention is to provide a new and improved method of attaching counterweights to crankshafts, which will insure rigidity and permanency to the connection.

Another object of the invention is to provide an elliptically shaped cheek on a crankshaft which is somewhat enlarged to obtain a shoulder, thereby eliminating use of a lobe normally provided on a conventional crankshaft cheek, thus simplifying the forging thereof.

Another object of the invention is to provide counterweights for crankshafts, which may be forged independently or cut from a flat ring into segments and may be riveted to a cheek provided on the crankshaft.

Engines designed to operate at high speed do not permit the fastening of counterweights to crankshafts thereof by simple instrumentalities such as bolts or welding and the required precise fitting for riveting is performed conventionally by expensive milling and fitting operations.

It is therefore another aim and purpose of the invention to provide a method of machining the crankshafts and counterweights, which permits the exclusive application of simple and inexpensive turning operations to obtain the necessary precision without fitting operations.

With the above and other objects and advantages in view, the invention consists of certain features of construction and operation of parts which will hereinafter be described and shown in the accompanying drawings, in which:

Fig. 1 is a cross-sectional end view of a crankshaft, including an elliptically shaped cheek, with a counterweight removed therefrom and illustrating the method of obtaining the necessary precision on the face of the cheek of the crankshaft by the simple turning operation thereof on a lathe for fitting a counterweight thereto;

Fig. 2 is a side elevation thereof;

Fig. 3 is an end view similar to Fig. 1, with the counterweight attached to the crankshaft cheek; and

Fig. 4 is a side elevation of Fig. 3 partly in section.

Referring more specifically to the drawings, there is shown in Figs. 1 and 2 a crankshaft 1 with the counterweight 2 (illustrated in Figs. 3

2

and 4) removed therefrom. The crankshaft 1 may be cast, forged or formed in any other suitable manner and is provided with cheeks 3 and 3' carrying an integral crankpin 4. The contour 5 of the crankshaft cheek 3 is elliptical and shaped by means of turning on a crankshaft lathe (not shown) to provide a circular arc 4' described about the center A of the crankshaft 1 with any desired radius *a* as shown in Fig. 1. The crankshaft cheek 3 is further turned on a lathe to provide a circular arc 5 described about the center B of the crankpin or member 4, with any desired radius *b* providing a flange 6 on the cheek 3 forming a shoulder 7 in the shape of a circular arc. Any suitable number of spaced arcuately aligned holes 8 may be provided in the flange 6 of the crankshaft cheek 3 for a purpose which will hereinafter appear. The outer periphery 9 and the inner face 10 of the flange 6, together with the periphery 11 of the shoulder 7 is turned on a lathe to the required precision whereby an arcuately shaped recess or seat is provided on the crankshaft cheek defined by two intersecting circular arcs. By providing a shoulder 7 on the crankshaft cheek 3, no lobe has to be forged on the crankshaft cheek, thus simplifying the forging operation.

Referring to Figs. 3 and 4, it will be seen that the counterweight 2 is in the form of an arcuate segment readily turned on a lathe to provide a flange 12 forming a shoulder 13. The peripheral face 14 of the counterweight shoulder 13 may be turned on a lathe around the common center A using the same radius *a* employed for turning the outer periphery 9 of the flange 6 of the crankshaft cheek 3 and the peripheral face 15 of the flange 12 on the counterweight may likewise be turned on a lathe around the common center B using the same radius *b* employed for turning the peripheral face 11 of the crankshaft shoulder 7 whereby an arcuately shaped recess is provided on the counterweight. The flange 12 of the counterweight 2 is provided with a series of spaced arcuately aligned openings 16 adapted to register with the holes 8 in the flange 6 of the crankshaft. Assuming that the peripheral face 14 of shoulder 13 on the counterweight 2, the peripheral face 15 of the counterweight flange 12 and the inner face 17 of the counterweight to have been turned on a lathe to the proper precision, then counterweight 2 may be readily fitted in the recess of crankshaft cheek 3, with the peripheral face 14 of the counterweight shoulder 13 abutting against the peripheral face 9 on the flange 6 of the crankshaft cheek 3, and the face 17 of the counterweight

flange 12 abutting against the face 10 of the crankshaft flange 6. The flange 12 of the counterweight 2 is secured to the flange 6 of the crankshaft 1 by means of rivets 18 or the like mounted in the aligned holes 8 and the openings 16 formed in the crankshaft flange 6 and the counterweight flange 12, respectively. It is within the purview of the present invention to make counterweight 2 removable for ready replacement, if desired, with a similar or different counterweight of the same configuration. To this end, rivets 18 may be replaced by suitable bolts. By virtue of the elliptical configuration of crankshaft cheek 3, when the counterweight 2, formed in the manner disclosed, is attached to crankshaft 1 the latter will be statically and dynamically balanced as will be understood without further discussion.

The counterweight 2 is forged individually, but a series of such counterweights may be arranged in a fixture as segments with a common center and turned on a crankshaft lathe only at their inner faces, or the counterweights may be cut from a flat ring into segments.

In the light of the above description, it will be seen that the instant invention provides a new and efficient counterweighted crankshaft and method of making the same, which is well adapted for the purpose intended.

Having thus described our invention, what we claim as new and wish to secure by Letters Patent is:

1. A counterbalanced crankshaft comprising main bearing segments, a throw segment intermediate the bearing segments, a cheek interconnecting each bearing segment with the throw segment, a smooth perforated member in one of the cheeks on a side thereof opposite to the throw segment and remote from the throw segment, a counterweight fixedly mounted on the member, the said counterweight having a smooth surface and perforations complementary to the smooth surface and perforations of the member, the entire mass of the counterweight being located on a side thereof opposite the throw segment at approximately the adjacent main bearing segment, and means connecting the counterweight to the member, the said counterweight and the said cheek forming substantially continuous side surfaces.

2. A counterbalanced crankshaft for an internal combustion engine comprising main bearing segments, throw segments intermediate said main bearing segments, said throw segments comprising cheeks and a crankpin connecting the said cheeks, a smooth perforated member formed adjacent to the juncture of the said main bearing segment and a cheek of the throw segment, a counterweight having a smooth perforated area

complementary to said smooth perforated member formed at the said juncture of the said main bearing segment and the said cheek of the throw segment, and fastening means fixedly securing the said counterweight to the said member in registering engagement and forming an integral structure having substantially continuous side surfaces, the entire mass of said counterweight being positioned opposite the main bearing segment on the side opposite the throw segment.

3. A counterbalanced crankshaft for an internal combustion engine comprising a main shaft, main bearing segments disposed along the said main shaft, cheek segments intermediate said main bearing segments, a crankpin intermediate said cheek segments, a smooth perforated member at the end of the said cheek segment opposite the said crankpin, means for securing a counterweight to said member, a one-piece counterweight including complementary surface and perforations fixedly secured to said smooth perforated member, said cheek segment and said counterweight forming substantially continuous side surfaces, the entire mass of the said counterweight being positioned at a radius from the said main shaft and on a side opposite the said crankpin.

4. A counterbalanced crankshaft comprising main bearing segments, cheek segments intermediate the bearing segments, a crankpin segment interconnecting the cheek segments, a smooth perforated member in one of the cheeks on a side thereof opposite the crankpin, a counterweight fixedly mounted on the member, the said counterweight having a smooth surface and perforations complementary to the member, the entire mass of the counterweight being located opposite the center of rotation of the crankshaft in relation to the crankpin, the counterweight and the cheek member forming substantially continuous side surfaces.
